UNITED STATES PATENT OFFICE

JOHN SNEED, OF DETROIT, MICHIGAN, ASSIGNOR TO THE MIDLAND STEEL PRODUCTS COMPANY, OF CLEVELAND, OHIO, A CORPORATION OF OHIO

BRAKE DRUM

Original application filed August 6, 1925, Serial No. 48,470. Divided and this application filed June 8, 1927. Serial No. 197,329.

This invention relates to brake drums, particularly to the shape of the periphery of the drum flange and to the relative form and position of the flange with regard to the contour and position of the backing plate. This invention is disclosed in copending application, Serial No. 48,470, filed August 6, 1925 for brake mechanism. This application comprises to that extent a division of my copending application.

One of the apparent advantages in the internal expanding type of brake is its freedom from grit or moisture. It has long been recognized that the presence of water between the friction surfaces may result in the loss of control of the car. The presence of grit between the braking surfaces causes a scoring and uneven wear which is highly detrimental and greatly shortens the life of the brake.

When a brake shoe is urged into engagement with a flanged brake drum, there is a tendency to distort the drum. If the drum be permanently distorted the effect will be to vary the clearance between the shoe and the drum so that an uneven engagement may result. The clearance may be reduced to so little that a continuous drag results, with consequent danger of heating and freezing of the brake. It is therefore among the objects of my invention to form a brake drum of great strength consistent with minimum weight which will effectively resist distortion and permit high braking pressures which might be non-uniformly exerted on the drum flange.

Another object is to position the reinforcing or strengthening means for the drum with relation to the backing plate to exclude foreign matter from the inside of the drum. Another object is to form the backing plate with regard to both the brake drum and the brake shoe to cooperate in carrying out the above object.

Other objects will appear from the following more detailed description of my invention. The essential characteristics are summarized in the claims.

In the drawing Fig. 1 is a partly broken elevation taken from the inner side i.e. facing the backing plate; Fig. 2 is a section taken along the line 2-2 of Fig. 1; Fig. 3 includes

three diagrammatic illustrations of drum distortion.

In the drawing I designate the drum having an outward face A and having the primary flange F. Concentric with the flange I show the shoe S which may be of any illustrative type. For convenience of designation I consider the face A of the drum as being on the outer side of the drum so that the flange F extends inwardly, that is, toward the center of the vehicle. The drum is flanged radially to provide an annular web W which serves as a radial reinforcement for the inner portion of the flange F.

Such a radial flange is common and has been thought heretofore to be adequate to support the flange. It has been my experience however, that when the shoe F is forcibly expanded that the web W tends to ripple or wave in a circumferential direction with the result that the inner portion of the flange F may be forced to describe an ellipse, while the outer portion of the flange F adjacent the face A is held to a circle. My experience has taught me that the web W or its equivalent alone is inadequate and that a harmful distortion of the drum is not prevented by its use alone.

In Fig. 3, I have shown diagrammatically the rippling or waving of a radial web at the brim of a distorted drum. The views a and b are taken at right angles to each other along the minor and major axes of the ellipse formed by the brim of the drum when it is distorted. Diagram c represents the normally formed drum.

To gain the desired stability and to stay within the limits of economy both of material and of manufacture, I have found it advantageous to form a second cylindrical flange FF which extends inwardly of the drum and lies coaxially of the flange F. The flange FF is integral with the web W and is adapted by reason of its position or rather by reason of its cylindrical shape, to withstand axial strains or forces delivered to it which are parallel to the axis of the drum. The tendency of the web W to ripple or wave delivers such strains to the flange FF in the form of unbalanced couples lying in the cylinder

described by the periphery of the web. I may conceive that these couples are measured between the nodes and troughs of the waves or ripples set up or tended to be set up in the web. The components of these couples, as mentioned above, lie in a cylinder of the periphery of the web and are taken up in the direction of axial dimension of the flange FF. The flange FF prevents rippling of the web W and the web W in turn being held against rippling holds the primary flange of the drum F to a true circle at its inner edge.

To maintain alignment of the shoe within the drum and to provide a means for taking the reactive torque of the brake application, a suitable member such as the plate P commonly called a backing plate is provided. In my preferred form shown herewith the backing plate P is made of material of sufficient weight to take the reactive torque from the brake shoe and deliver it to the axle of the vehicle. In such a backing plate the middle portion is formed to be secured to the axle or steering knuckle as the case may be. For the purpose of my present invention, I am concerned with that annular portion of the backing plate which lies near the surface of the shoe S and extends radially and inwardly (relative to the vehicle) toward the brim of the drum. The backing plate may lie close to the shoe and serve to guide it as at 1. The peripheral portion of the backing plate comprises an annular offset portion 2, which includes a circumferential flange 3 and a radial flange 4. The inwardly facing surface of the radial flange 4 may lie in substantially the plane of the brim of the drum. The radial dimension of the flange 4 may conform to the depth of the web W so that a clearance is provided between the backing plate and the flange FF of the drum as at 5.

The radial dimension of the web W and consequently the flange 4 determine the distance between the opening 5 and the surface of the shoe S. Inasmuch as the flange FF lends strength to the web W, the web may be given a greater dimension than has heretofore been found practical. The result of this is that a comparatively long and tortuous path must be traversed by moisture or grit which is thrown into the opening 5. Opposed to the ingress of such moisture or grit is the centrifugal force caused by rotation of the drum. It has been my experience that the combination of a drum so formed with a backing plate as shown comprises a highly effective protection against extraneous matter.

From the foregoing description of my invention it appears that I have provided a drum of great strength for a minimum gauge of material and one that is susceptible of cheap and efficient manufacture. The rigidity of the drum permits a smaller clearance between the brim of the drum and the back-

ing plate so that foreign matter is more completely excluded. I have shown herewith a preferred form of my invention, but I do not care to be limited other than by the claims appended hereto.

I claim:

1. The combination of a brake drum for a vehicle brake having a main cylindrical flange and an L shaped flange formed on the open inner edge thereof and facing inwardly with respect to the vehicle, and a relatively fixed member having an annular part proximate the said L-shaped flange for excluding foreign matter from the drum said relatively fixed member lying at least radially within the said L-shaped flange.

2. The combination of a brake drum having an L shaped flange extending beyond the open inner edge of the said drum and a backing plate having its periphery disposed in close proximity to and within the centrally facing portion of the L shaped reinforcing flange.

3. The combination of a brake drum having an L shaped flange extending beyond the body of the drum and forming the brim thereof, and a backing plate having its periphery disposed in close proximity to the centrally facing portion of the L shaped reinforcing flange, said backing plate lying substantially within the plane of the brim of the drum.

4. The combination of a brake drum having a main cylindrical flanged portion and a cylindrical reinforcing flange of greater diameter than the main flange and lying concentric therewith, and a backing plate the periphery of which extends beyond the diameter of the main cylindrical flanged portion and lies in close proximity with and within the said auxiliary reinforcing flange.

5. The combination of a brake drum having a main cylindrical flanged portion and an L shaped reinforcing flange formed on the inner edge thereof, and a backing plate having an annular peripheral off-set portion disposed in close proximity to and radially within the centrally facing portion of said L shaped reinforcing flange.

6. The combination of a pressed metal brake drum having a main cylindrical flange providing a cylindrical braking surface, a brake shoe disposed in operative relation to said braking surface of the drum, a backing plate disposed adjacent the said brake shoe and engageable therewith adjacent the periphery thereof and adapted to limit the lateral movement thereof, said brake drum having an L shaped reinforcing flanged portion formed on the inner open edge thereof, the backing plate having an annular inwardly off-set portion extending beyond the cylinder described by the braking surface of the drum and into close proximity with the centrally

facing portion of the said L shaped reinforcing flange.

7. A brake drum formed of relatively light sheet stock and pressed to shape having a main flange providing a braking surface and a cylindrical reinforcing flange lying concentric with said main flange and being of greater diameter than said main flange and extending beyond said main flange, and being joined integrally with said main flange whereby the full strength of the stock is developed and the drum is held against distortion, in combination with a back plate the periphery of which is proximate to and radially and axially within the said cylindrical reinforcing flange.

8. A pressed metal brake drum formed of light sheet stock comprising a main cylindrical portion providing a braking surface, a radial web formed at the edge of said main cylindrical portion, a reinforcing cylindrical ring for said web of substantially the same size of said web and formed integral with said web and lying concentric with said main cylindrical portion and extending inwardly of said drum, whereby the ring reinforces the web and develops the full strength of the stock while holding the drum against distortion.

9. A pressed metal brake drum formed of relatively light sheet stock having two integrally formed auxiliary reinforcing flanges after flanges of substantially the same size, one of which is formed on the brim thereof, said auxiliary flanges being disposed at right angles to each other and mutually supporting each other, one holding the other from rippling and the latter holding the former from radial distortion.

40 In testimony whereof, I hereunto affix my signature.

JOHN SNEED.
